Primary Examiner — Nathan M Johnston

(57) **CLAIM**

The ornamental design for a peg board as shown and described.

DESCRIPTION

FIG. 1 is a right, front, top perspective view of a peg board showing my new design;

FIG. 2 is a left, rear, bottom perspective view thereof;

FIG. 3 is a right side elevational view thereof;

FIG. 4 is a left side elevational view thereof;

FIG. 5 is a front plan view thereof;

FIG. 6 is a rear plan view thereof;

FIG. 7 is a top elevational view thereof; and,

FIG. 8 is a bottom elevational view thereof.

The broken lines in the drawings depict portions of the peg board that form no part of the claimed design.

1 Claim, 8 Drawing Sheets
